UNITED STATES PATENT OFFICE.

CHARLES S. PIERCE, OF BROCKTON, MASSACHUSETTS.

SHOE-FORM.

1,078,554.

Specification of Letters Patent.

Patented Nov. 11, 1913.

Application filed April 1, 1909. Serial No. 487,152.

To all whom it may concern:

Be it known that I, CHARLES S. PIERCE, a citizen of the United States, residing at Brockton, county of Plymouth, State of Massachusetts, have invented a certain new and useful Improvement in Shoe Forms, of which the following is a specification, reference being had therein to the accompanying drawings.

10 Shoe salesmen find it necessary to carry with them considerable numbers of sample shoes. In order that these shoes may be kept in the best condition and in order also that they may appear to the best advantage 15 when they are exhibited to probable purchasers it is necessary that each shoe be provided with a form which fits inside the shoe and serves to fill the shoe and to hold it out to shape. The shoes are carried by traveling salesmen in trunks and are frequently taken out to be displayed and are then repacked in the trunks. As the trunks are 20 often filled to their capacity the shoes require to be crowded down closely one upon 25 the other in order to get them into the trunk and in doing this they are frequently subjected to very considerable pressure and unless the forms used in the shoes are strong 30 they are apt to be broken down or split and destroyed. As it is important that the trunks of the salesmen be as light as possible it is desirable that the forms used should be 35 light, strong and be properly shaped to fill out the shoe and therefore give the greatest efficiency.

My invention has for its object to provide a shoe form which shall have the desirable qualities above enumerated and it consists 40 in a form constructed as hereinafter set forth, and as shown in the accompanying drawings, the novel features of which are pointed out and clearly defined in the claims at the close of the specification.

45 In the drawings, Figure 1 is a plan view of a shoe form embodying my invention. Fig. 2 is a side view partially broken away for greater clearness in showing the construction. Fig. 3 is a bottom view in plan, and Fig. 4 is a section on line 4—4 of Fig. 2. 50 Referring to the drawings, A represents the fore part of the form which is of a shape to fit the inside of the shoe for which the form is designed. This fore part is preferably made of paper board which is molded 55 to shape in the well known manner; the fore part is preferably of a length sufficient to

fill the entire fore part of the shoe from the ankle forward. The sole, which when the form is in place lies against the sole of the shoe, is cut away, as shown at B, Fig. 3, and across this open cut-away portion is secured 60 a cross piece D preferably of metal or other rigid material. The ends of the cross-piece D are riveted as at 2, or otherwise secured by eyelets or the like to the turned edges 65 3 of the sole of the form. The employment of the cross piece D insures great rigidity and strength together with lightness. The form on the sole rearwardly of the opening B is formed entire as shown Fig. 3, the 70 two edges of the material of which the fore part is formed being brought together on the line 4. Inside the form at this shank portion I place a shank shaped strip 5, see Fig. 2, of leather board, or other suitable material, the rearward portion 6 of which projects into the heel of the shoe and serves to hold the form in position in the shoe. Near the heel end of the part 6 I form a hole 7 and place therein a piece of string 8 75 by which the heel portion 6 may be lifted and the form withdrawn from the shoe if desired. 80

The shank strip 5 is secured in place by means of rivets 9 which pass through the sole portion of the shank of the form and through the said shank strip. I preferably employ six of these rivets as shown in order to insure strength and rigidity. Within the said fore part above the shank portion I 90 place a continuous rib or band of metal 10 which is secured in place preferably by two-pronged rivets which are passed through from the outside and the prongs of which are clasped over the metal brace 10 as shown. 95 I preferably employ three or more of these rivets. This metal reinforce or rib 10 should be of sufficient size to support the fore part at the instep and prevent it from being broken down or split, even under very 100 severe pressure. In practice I form this reinforcing rib or brace of iron wire of about No. 11 gage. A piece of this wire is cut to the proper length and the two ends are secured together preferably by electric welding. The ring of wire thus formed is then shaped to the interior cross-sectional shape of the form at the instep, is inserted in place and is then secured firmly by means of the two-pronged rivets as heretofore described. 110 The ring of wire should fit the interior of the form with considerable accuracy for the

very best results, but it is not necessary that it should fit accurately especially at the top portion of the form for without fitting with great accuracy it forms a sufficiently strong brace or reinforce to wholly prevent the form from collapsing or splitting under any pressure to which the shoe is likely to be subjected. In order that the wire ring may be shaped by a former to varying contours of different shoe forms, the wire is preferably of malleable iron yet sufficiently stiff to retain its form when shaped.

I have described the form as made from paper board and I find this material to be especially well adapted for the purpose. It will be obvious however that it may be made from leather or fabric properly treated or from other flexible sheet material which is capable of being molded accurately to shape.

Forms embodying my invention are relatively inexpensive, are light, and are very efficient in service.

What I claim is:—

1. A hollow shoe form having a fore part portion consisting of a shell of molded material adapted to fit the fore part of a boot or

shoe and having in its interior a single non-contractible endless ring shaped to conform substantially with the cross-sectional interior contour of the shoe in the instep portion thereof, and contacting substantially throughout with the top, sides, and bottom and secured to the sides and bottom of the shoe form.

2. A hollow shoe form having a fore part portion consisting of a shell of molded material adapted to fit the fore part of a boot or shoe, an endless wire ring shaped to conform substantially with the cross-sectional interior of the instep portion near the highest part thereof and contacting substantially throughout its length with the interior top, sides and bottom of the shell and means whereby said band is secured to the sides and bottom and shank portion of said forms.

In testimony whereof I affix my signature, in presence of two witnesses.

CHARLES S. PIERCE.
